(57) **CLAIM**

The ornamental design for a “combination document tray and drawer,” as shown and described.

DESCRIPTION

FIG. 1 is a perspective view of a first embodiment of a combination document tray and drawer showing my new design;

FIG. 2 is a front elevational view of the combination document tray and drawer of FIG. 1;

FIG. 3 is a left side elevational view of the combination document tray and drawer of FIG. 1, the right side elevational view being a mirror image thereof;

FIG. 4 is a rear elevational view of the combination document tray and drawer of FIG. 1;

FIG. 5 is a top plan view of the combination document tray and drawer of FIG. 1;

FIG. 6 is a bottom plan view of the combination document tray and drawer of FIG. 1;

FIG. 7 is a perspective view of a second embodiment of the combination document tray and drawer;

FIG. 8 is a front elevational view of the stack of FIG. 7;

FIG. 9 is a left side elevational view of the stack of FIG. 7, the right side being a mirror image thereof;

FIG. 10 is a rear elevational view of the stack of FIG. 7;

FIG. 11 is a top plan view of the stack of FIG. 7;

FIG. 12 is a bottom plan view of the stack of FIG. 7;

FIG. 13 is a perspective view of a third embodiment of the combination document tray and drawer;

FIG. 14. is a front elevational view of the combination document tray and drawer of FIG. 13;

FIG. 15 is a left side elevational view of the combination document tray and drawer of FIG. 13, the right side being a mirror image thereof;

FIG. 16 is a rear elevational view of the combination document tray and drawer of FIG. 13;

FIG. 17 is a top plan view of the combination document tray and drawer of FIG. 13;

FIG. 18 is a perspective view of a fourth embodiment of the combination document tray and drawer;

FIG. 19 is a front elevational view of the stack of FIG. 18;

FIG. 20 is a left side elevational view of the stack of FIG. 18, the right side being a mirror image thereof;

FIG. 21 is a rear elevational view of the stack of FIG. 18; and,

FIG. 22 is a top plan view of the stack of FIG. 18.

The dashed lines are for illustrative purposes only and form no part of the claimed design.
